UNITED STATES PATENT OFFICE.

BENJAMIN F. BUTLER, OF DAVENPORT, IOWA.

THREE-WHEEL RIDING-PLOW.

SPECIFICATION forming part of Letters Patent No. 357,574, dated February 15, 1887.

Application filed July 16, 1886. Serial No. 208,214. (No model.)

To all whom it may concern:

Be it known that I, BENJAMIN F. BUTLER, a citizen of the United States, residing at Davenport, in the county of Scott and State of Iowa, have invented new and useful Improvements in Three-Wheel Riding-Plows, of which the following is a specification.

My invention consists of contrivances for the mounting of the plow on the saddle or beam of a three-wheel riding-plow having a cranked front axle and main wheels, with a rear caster-wheel, in an arrangement enabling the plow to be lowered into and raised out of the ground by the sliding of the stock in vertical ways of the beam or saddle, with suitable toothed rack, pinion, lever, and friction-roller mechanism for so operating the plow, by which more substantial and efficient apparatus may be employed than when the beam or saddle is made to rise and fall for the purpose; and my invention also consists of improvements in the tongue, colter, and evener apparatus for greater simplicity and efficiency, all as hereinafter fully described, reference being made to the accompanying drawings, in which—

Figure 1 is a side elevation with the land-side wheel removed by the section of the axle on the line $\alpha\alpha$ of Fig. 2. Fig. 2 is a plan view, with some parts in section. Figs. 3, 4, and 5 are details, on an enlarged scale, of the plow-connection, with the saddle or beam in side elevation, plan, and in front elevation and transverse section of the beam at $y\gamma$. Fig. 6 is a section of the pivot-joint of the 35 caster-wheel. Fig. 7 is a detail of the beam contrivance.

For the beam or saddle a , I use an angle-bar, making a socket, b , at the rear end for the pivot-stock c of the caster-wheel d , and fork-arms e at the front end, with bearing holes or sockets by which to mount it on the cranked axle f of the main front wheels, g , and about midway between the front and rear ends of this beam or saddle I provide the vertical slideway h in 45 one side of the beam for the stock i of the plow j , which I fit in said slideway suitably for being shifted up and down and for being held firmly at any point with friction-rollers k and l , suitably located in said slideway to take the 50 thrusts of the front and back edges of the stock, respectively, and relieve the friction of the

slide, thus providing a simple contrivance for the mounting of the plow, so that it may be adjusted on the beam in a simple way, instead of adjusting the beam on the axle, and enabling 55 the beam to be connected to the axle without adjustment other than the turning of the axle in the bearings of the beam.

The beam a is constructed with a vertical extension, m , above and below for suitable 60 breadth to afford substantial holding for the plow-stock, in which the slideway is placed under the solid lip n at one side, and for the attached retaining-cleat o of the other side, the said extension being made thicker on the 65 side having the solid lip n than on the other side, to provide for said solid lip and also for the substantial support of the friction-roller l and the pivot o^2 of the pinion x and ratchet-wheel y , by which the stock is in this example 70 to be worked. For the attached retaining-cleat o of the other side of the slideway of the plow-standard I utilize one edge of the rack-plate s , employed for locking the shifting-lever t by the stop-latch u , to hold the plow when 75 set, said plate being applied so as to overlap the slideway suitably for such cleat, and it is secured by the bolts v , one of which forms the pivot of friction-roller k , which is fitted in a recess of extension m under the rack-plate. 80

The plow-stock is in the present case provided with a rack-plate, w , that gears with the pinion x on the pivot o^2 , which pinion is turned by the ratchet-wheel y , also attached to said pivot, and provided with the lever t and latch 85 z for shifting it, and with the dog a' for holding it, said dog being pivoted to the beam at b' and the lever being pivoted loosely on the pivot o^2 .

The lever t and latch z are used in some 90 cases for holding the plow in position without the dog a' , and particularly for shifting the plow up or down through a short range to vary the depth of the furrow to some extent, the lever being set along the rack s and held 95 in it by the latch u , which, together with the latch z , is connected to one trip-handle c' of the lever, but on a greater radius than that of said latch u , so that a partial throw of the trip-handle will detach latch u and leave latch 100 z engaged with the ratchet, to allow the lever to swing and shift the ratchet, and a further

movement of said trip-handle will detach both latches when latch z is to be shifted along the ratchet-wheel for greater shift of the plow-stock, the ratchet then being held by the dog a .

5 It is obvious that a lever having a toothed segmental arm gearing directly with the rack w may be substituted for the pinion y and its ratchet mechanism if desired. The contrivances of the guideway may also be modified 10 if desired.

For shifting the cranked axle f , to adjust the furrow-wheel for the furrow or for the surface, the tongue d' , which is mounted above the axle by the bearing-bar e' , holding it a suitable distance above the axle, is provided with a segmental toothed holding-rack, f' , and the lever g' is rigidly attached to the axle suitably for swinging along the rack, and provided with the stop-latch h' , engaging the rack to hold the 20 lever and the axle at any position along the rack. The tongue is pivoted to the front end of the bearing-bar e' at e^2 , and connected to the rear end of said bar by the slotted and toothed arm f^2 , the bolt g^2 being adapted to shift in 25 said slot by the stop-latch h^2 , so that by releasing the stop-latch the tongue can swing to some extent to relieve the lateral stress. In this case the arrangement is represented for turning the team to the left hand only, which 30 is generally the way the team turns; but I contemplate arranging it to turn either way.

The revolving colter i is pivoted in the forked arm j' , extending rearward from the joint k' , with the lower arm of a lever, l' , pivoted on the axle and extending downward and forward to said joint k' , and having a latch, m' , that engages the sector m^2 , attached to the axle for setting the colter higher or lower by swinging the lever accordingly. The joint k' 40 is adapted for shifting the colter laterally to set it in alignment with the plow.

For a dust-proof and durable pivot joint of the caster-wheel I make the hub n' with the countersunk cones p' and shoulders q' at the 45 bases of the cones, and provide the reversely-shaped caps s' , adapted to fit snugly on the shoulders q' , also on the sides of the cones and in the countersunk sockets of the cones, and secure said caps by the pin t' and the bosses w' of the forked stock c , the pin, which is secured in the hub by casting the hub on it, extending through the caps and entering into sockets of the bosses, the arms of which spring the bosses into sockets w' in the exterior of 55 the caps and onto the ends of the pin, thus making a joint that is constantly pressed tight by the spring of the arms of the fork without the use of any nuts, keys, or other devices adapted to wear slack. The bosses of the 60 forked arms constantly bear on the metal at the bottoms of the sockets, where the contact is between the rotating and the stationary parts, and prevent the dust from working farther into the joint.

65 For attaching the evener by a contrivance enabling the point of connection to be shifted laterally, as may be required, for regulating the

draft, and at the same time being simple to construct and substantial in wear, I make a yoke or bow, x' , of somewhat more than half a circle, and pivot it on the axle at y' , each side of the beam between the saddle-bearings on the axle, with arms z' , extending backward from the axle under the saddle-arms and connected thereto, for supporting the yoke in the horizontal position, and about midway between the axle and the front end of the yoke I arrange the attaching-bar a^2 on the arms of the yoke and parallel to the axle, and having a series of clevis-pin holes, b^2 , at intervals along it, in which to connect the evener as required.

The axle turns in the bearings of the yoke, and the arms of the yoke, being connected to the arms of the saddle, maintain the yoke in the required horizontal position without interference of the axle by turning to adjust the crank.

Although I have described and represented a vertical slideway for the plow-stock, I do not mean to be limited strictly to the vertical 90 direction, for it is obvious that it may be more or less inclined without detriment for my purpose, and my invention includes any practical inclination.

Having thus described my invention, what 95 I claim, and desire to secure by Letters Patent, is—

1. The combination, with the plow having the stock fitted to the beam or saddle in a slideway, and provided with the toothed rack, 100 of the ratchet-lever, ratchet-wheel, and pinion gearing with said rack of the plow-stock, the stop-rack and latch for holding the lever, and the trip-handle of the ratchet-lever, said trip-handle being differentially connected with 105 said latches, substantially as described.

2. In the construction of the slideway of the beam for the plow-stock, the detachable lip thereof consisting of the stop-rack plate of the adjusting-lever, attached to the beam or 110 saddle, with one edge overlapping the slideway, and thereby also constituting the detachable retaining-lip of said slideway, in combination with the integral or other retaining lip of the opposite side of said slideway, substantially as described.

3. The combination, with a wheel-plow, of the revolving disk-colter attached to the lower projecting arm of the lever, pivoted on the axle, and provided with a stop-rack and latch for setting it in different positions by the swing of the colter with the lever, substantially as described.

4. The combination, with a wheel-plow, of the revolving disk-colter attached to the 125 lower projecting arm of the lever, pivoted on the axle by the forked arm, jointed to said arm of the lever for lateral or horizontal adjustment, substantially as described.

5. The combination, with the countersunk and shouldered cones of the caster-wheel hub, of the reversely-formed caps, pivot-pin, and the spring-arms of the fork, said arms having the bosses fitted in the recesses of the caps,

and the caps fitting in the sockets over the cones and against the shoulders thereof, substantially as described.

6. The combination, with the cranked axle of a wheel-plow, of the evener-yoke pivoted to the axle and connected to the beam-arms by the rearwardly-extending arms, and having the hitching-bar for connecting the evener

located in advance of and parallel to the axle, and having a series of holes for the clevis-pin, substantially as described.
